UNITED STATES PATENT OFFICE.

ALBERT G. DESHAZO, OF CYPRESS RIDGE, ARKANSAS.

CAR-COUPING.

SPECIFICATION forming part of Letters Patent No. 402,572, dated May 7, 1889.

Application filed May 25, 1888. Serial No. 275,093. (No model.)

To all whom it may concern:

Be it known that I, ALBERT G. DESHAZO, a citizen of the United States, residing at Cypress Ridge, in the county of Monroe and State of Arkansas, have invented certain new and useful Improvements in Car-Couplings; and I do hereby declare the following to be a full, clear, and exact description of the invention, such as will enable others skilled in the art to which it appertains to make and use the same.

My invention relates to improvements in car-couplings, the object of which is to provide a cheap, simple, and durable device for coupling and uncoupling cars. These objects I attain by means of the device illustrated in the accompanying drawings, forming a part of this specification, in which—

Figure 1 is a view in elevation of the entire device. Fig. 2 is a view of one of the couplers detached. Fig. 3 is a view of the opening roller.

Similar letters of reference represent corresponding parts in the several figures.

A is a draw-head or bumper of any desired size and shape, to which the coupling device is attached, either above or below, in any desired way, so as to revolve and present either end or either side forward. For this purpose the coupling B has a hole, b, provided with a king-bolt, b², which enters the draw-head of the car. Said coupling B is thus permitted to revolve, and for the purpose of holding it with either end or side forward the draw-head and coupling-block B may be provided with a longitudinal and cross tongue, b³, and groove b⁴ or any other suitable device for holding it in the desired positions for coupling by presenting the proper end, or by preventing a coupling by presenting one of the sides, so that cars may be pushed in switching without coupling.

One end of the coupling is provided with a spear-head, C, for entering the coupling-block of the other car. The other end is provided with a trap, D, formed by the upper and lower plates, d d², and the movable side jaws, d³. Said movable jaws are hinged by bolts d⁴ near the end of the coupling, and are provided with projections d⁵, at the inner ends, which extend up through slots b⁶ in the coupling-block.

E are springs for holding the inner ends of

the jaws together. For this purpose they are bolted at one end, e, to the coupling-block 55 in any suitable way, while the other end, e², is free and rests against the outside of the inner ends of the jaws d³ for holding them together and causing them to catch the spear-head of the coupling-block of the other car 60 automatically when the cars are shoved together, and thus couple the cars.

F is a roller, forming cams or inclined edges f², against which the projections d⁵ of the jaws rest, so that the jaws may be opened 65 and the cars uncoupled by turning the roller F. For this purpose said roller may be provided with a lever or crank, f, or other suitable device for turning the same.

Thus I have a device either end of which 70 may be presented for the purpose of automatically coupling cars together, and the side of which may be presented for the purpose of preventing a coupling when desired. The lever or projection f⁷ is formed to enter a 75 slot, d⁷, in the plate d, so as to rest by the side of the neck C² of the spear-head C, so that as the head is drawn out its shoulder C³ strikes the said projection f⁷ and throws it back up, and thus causes the jaws to close as 80 the spear-head comes out. The cranks f are placed on each end of the roller F, so that the cars may be uncoupled from either side of the car, and for this purpose the said roller has suitable bearings, f⁶ f⁶, on the plate d. 85

Said coupling may be placed on the under side of the draw-head by properly arranging the same with reference to the draw-head.

Having thus described my invention, what I claim as new, and desire to secure by Letters 90 Patent, is—

In a car-coupler, the combination, with the draw-head B, having a transverse slot in its upper face, of the cam d⁵, working in said slot, the arm f⁷, secured rigidly to the cam-supporting bar and working in a longitudinal opening in the draw-head, the jaws d³, located in the draw-head, and springs E², for forcing the jaws in, substantially as described. 95

In testimony whereof I affix my signature in 100 presence of two witnesses.

ALBERT G. DESHAZO.
